UNITED STATES PATENT OFFICE.

THOMAS C. LANE, OF BALTIMORE, MARYLAND.

CARPENTER'S TRANSIT.

Application filed April 20, 1921. Serial No. 462,788.

To all whom it may concern:

Be it known that I, THOMAS C. LANE, a citizen of the United States, residing at Baltimore, in the city of Baltimore and 5 State of Maryland, have invented certain new and useful Improvements in a Carpenter's Transit; and I do hereby declare the following to be a full, clear, and exact description of the invention, such as will enable others skilled in the art to which it 10 pertains to make and use the same.

The object of the invention is to provide a simple and efficient apparatus in the nature of a transit for the use of carpenters 15 for example in leveling and laying off walls, foundations, cellar bottoms and the like, but equally adapted for use by other mechanics in similar operations where accuracy is required in following plans, directions and 20 measurements; and the particular object in view is to provide an apparatus having the functions and capabilities indicated which will not involve the cost of production incident to the transits and like instruments, 25 used by surveyors and which are unnecessarily complicated and expensive for the purpose of the mechanic as above outlined; and with these objects in view the invention consists in a construction, combination 30 and relation of parts of which a preferred embodiment is shown in the drawing, wherein:

Figure 1 is a front view of the apparatus.

Figure 2 is a plan view thereof.

Figure 3 is a side view partly in section.

Figure 4 is a perspective view of one of the sighting blocks and

Figure 5 is a perspective view of the other 40 sighting block.

The apparatus consists essentially of a turntable comprising the upper revoluble plate 10 and a lower fixed plate 11 of which the former is pivotally mounted centrally 45 upon the latter, a supporting frame of the tripod form having a base 12 which supports the lower fixed plate or disk of the turn table which is attached thereto by securing screws 13, and the hingedly mounted 50 folding legs 14 secured to the base, and a sighting member or frame 15 carried by the revoluble plate or disk of the turn table and adapted to be moved therewith to occupy any desired angular position or to

be moved to any desired degree of angular 55 variation in a horizontal plane or in a plane perpendicular to the axis of the revoluble plate or disk 10.

The revoluble disk or plate in addition to being capable of movement upon a central 60 axis consisting in the construction illustrated of a pivot bolt 16 extending downwardly through enlarged central opening in the fixed plate or disk 11 and the base 12, after initially positioning the apparatus is 65 adapted to be accurately adjusted angularly or leveled by means of leveling screws 17 of which four are shown in the drawing with their thumb heads 18 located below the plane of the undersurface of the base 70 block 12, the guide in leveling the same consisting of any suitable form of leveling device such as the spirit level 20 on the sight frame which is carried by the revoluble disk or plate, said leveling screws bearing terminally against the under surface of the disk or plate 10 and the spindle or pivot bolt 16 extending loosely through the opening provided for its reception in the base block and 75 lower stationary disks 11 and being fitted with a coiled spring 21 bearing at its upper end against the under surface of the fixed plate or disk 11 and at its lower end upon a thumb nut 22 which may be adjusted 80 to vary the tension of said spring and 85 which for that purpose is threaded upon the lower end of said spindle or pivot bolt.

In the construction illustrated the sighting member or frame consists of the parallel upper and lower bars 23 and 24 connected by upright 25, and fitted upon the upper bar for adjustment longitudinally thereof are the sighting blocks 26 and 27 having an interlocking connection with the bar as by a dove-tailed joint 28 and being 90 adapted to be secured at the desired adjustment by set screws 29. One of the sight blocks is provided with a peep sight 30, and the other with an object opening 31 fitted with cross-hairs 32 to insure accuracy in 95 100 sighting.

Having thus described the invention, what I claim is:—

An instrument of the class described having a disk-like base, supporting legs pivoted thereto, a fixed disk-like plate on said base, a disk-like transit plate above said fixed plate, said base and plate being substan-

tially in superposed relation, a bolt depending from the transit plate and loosely into the fixed plate and base and below the base to permit rotation, axial sliding and tilting movement of the transit plate with respect to the fixed plate, a spring surrounding said bolt below the base and urging the

transit plate toward the fixed plate, an adjusting nut on said bolt engaged by said spring, and a plurality of leveling screws 10 extending through the base and fixed plate adapted to engage the transit plate.

In testimony whereof I affix my signature.

THOMAS C. LANE.
